Samuel Halaby, Inc., Rochester, N.Y.

Filed Apr. 16, 1962, Ser. No. 69,718

Term of patent 14 years

(Cl. D31—3)

Fig. 1

Fig. 2

Fig. 3

FIG. 1 is a perspective view of my new design for a sprayer, the side not shown being substantially identical to the illustrated side;

FIG. 2 is a left hand end elevational view of the sprayer shown in FIG. 1. The handle is shown broken away in FIG. 2 for convenience of illustration; and

FIG. 3 is a side elevational view of my sprayer shown in FIG. 1.

The essential features of my design reside in the solid line portions.

I claim:

The ornamental design for a sprayer for insecticides or the like, substantially as shown and described.
